UNITED STATES PATENT OFFICE.

WILLIAM W. McCCLAY AND CLARENCE GILBERT McCCLAY, OF CHICAGO, ILLINOIS.

CRATE.

1,277,094.

Specification of Letters Patent. Patented Aug. 27, 1918.

Application filed March 8, 1918. Serial No. 221,177.

To all whom it may concern:

Be it known that we, WILLIAM W. McCCLAY and CLARENCE G. McCCLAY, citizens of the United States, residing at Chicago, in 5 the county of Cook and State of Illinois, have invented new and useful Improvements in Crates, of which the following is a specification.

The crate which is the subject matter of 10 the present application for patent is designed more particularly for use in shipping sewing machines, and the invention has for its object to provide a simple, strong and durable crate for this purpose, and also one 15 which is collapsible or foldable into small and compact form so that it can be returned to the shipper at a small cost for re-use.

With the object stated in view, the invention consists in a novel combination and arrangement of parts to be hereinafter described and claimed, and in order that the same may be better understood, reference is had to the accompanying drawing forming a part of this specification. The preferred 25 embodiment of the invention has been illustrated, but it will be understood that various modifications may be resorted to without departure from the spirit and scope of the invention as claimed hereinafter.

30 In the drawing—

Figure 1 is a perspective view of the crate;

Fig. 2 is a diagram illustrating the manner in which the crate is foldable;

35 Fig. 3 is a sectional detail; and

Fig. 4 is a perspective view of a joint employed at one end of the crate.

The crate is made of metal tubing and is of rectangular skeleton form, the tubing 40 being arranged and connected in the following manner:

Two laterally spaced tubes 5 have upward bends 6 at their ends where they are continued to a suitable height to form vertical 45 end posts 7 which latter are connected by intermediate longitudinal spacers 8 and 9, and a top rail 10. These parts form the sides of the crate, the same being held in spaced relation by tubular cross bars 11, 12 and 13 at one end, and similar cross bars 50 11^a, 12^a and 13^a at the opposite end, the cross bars 13 and 13^a being at the bottom. The cross bars 11 and 11^a are near the top. These cross bars extend between and are connected 55 to the posts 7. The sides of the crate are also provided with bottom corner braces 13^b,

and a longitudinal rail 14 connects the top cross bars 11 and 11^a.

The connections between the several pipe or tube sections is made by T-coupling members 15, the stem of the coupling being inserted into the pipe end. The coupling members connecting the parts which make up the sides of the crate are firmly secured by screws 16 or other suitable fasteners. 60

The coupling members 15 for the cross bars 11, 12, 13, 11^a, etc., are loose on the posts 7 so that the latter are free to turn therein. It will therefore be seen that there is provided a pivotal connection between the cross 70 bars and the posts, and the crate may be folded, this being done by swinging the cross bars to extend obliquely between the sides, which brings the sides closely together. This action is illustrated diagrammatically 75 in Fig. 2 which shows at A the normal position of the crate; at B the partly folded position and at C the crate is shown completely folded.

Before the crate can be folded as described, the top rail 14 must be removed, and in order that this may be readily done, its ends are provided with knuckles 17 and 17^a to receive the cross bars 11 and 11^a, respectively. The knuckle 17^a is forked to straddle 80 the cross bar 11^a. The cross bar 11 is in two alined sections having their abutting and slightly reduced ends seating in the knuckle 17, and their outer ends seating slidably over the stems of the coupling members 15 by which they are connected to the posts 7. Hence, it will be seen that the two sections of the cross bars may be slipped out of the knuckles 17, which disconnects the rail 14 from the cross bar 11, permitting 95 said rail to be removed from the cross bar 11^a and enabling the crate to be folded. When the rail 14 is in place it serves as a guard for the sewing machine, protecting the top of the latter from injury by a heavy 100 object placed upon it.

The length of the crate conforms to the length of the machine body, but as the legs of the machine are usually closer together, a short platform 18 is mounted on each 105 bottom bar 5, on which the legs rest. The top rail is rounded near its ends, as shown at 19, to slope over the superposed boards forming the machine top or table. The top rails 10 are offset inwardly from the sides 110 of the crate sufficiently to overhang the top of the machine.

Suitable sheet metal guard plates 20^a are provided for the sides of the crate, these being shaped to fit under the top rails 10, and their purpose being to shield the machine from being marred by the crate. Similar shields or guards may be provided for the crate ends.

The crate is designed with one of its ends removable, to permit a sewing machine to be moved into the crate preparatory to assembling the latter for shipping. The cross bars 11, 12 and 13 are designed with a locking device in their ends to permit said cross bars to be quickly connected and locked to the coupling members 15 when the crate is assembled, and as quickly disconnected and removed when the crate is to have one end open for the removal of its contents.

The locking device mentioned above, and shown in Fig. 4, comprises opposed grooves 20 cut into each of the cross bars 11, 12 and 13, at both ends, the inner end of said grooves assuming a lateral course, as well as a curvature, to correspond with the curvature of the inner surface of the cross bar, as shown at 21; and studs 22 projecting from opposite sides of the stems of the coupling members 15. To make the connection between a coupling member and the end of a cross bar, the stem of the coupling is inserted into the end of the cross bar with the studs 22 disposed in the grooves 20, and, when the inner end of the latter is reached, the cross bar is twisted sidewise to locate the studs in the extensions 21 of the grooves 20, thus locking the cross bar from withdrawal. As shown, the groove extensions are directed in opposite ways to secure combined locking action when the cross bar is twisted.

In order to set up the crate for receiving a machine which is to be shipped, the crate is first opened from the position of diagram C of Fig. 2 to that of diagram A; the machine is next moved into the space within the crate to rest on the platforms 18; and finally, the sides of the crate are slightly spread to permit the application and locking of the top bar 14, and cross bars 11, 12 and 13, thus rendering the shipment ready for handling. It will be understood, of course, that the above described locking device represents but one means for securing the open end of the crate; various other locking devices adaptable to the design of the crate may be used, and we do not wish to restrict our claim to the form of locking device illustrated in the present instance.

The structure hereinbefore described provides a light, strong and durable crate, and also one which can be folded into small and compact form for convenient and cheap re-

turn to the shipper, and although the crate is designed more particularly for sewing machines, it will be understood that the structure can also be employed in connection with crates for shipping other articles of merchandise. The invention is also not limited to tubing, but any other suitable light and strong material may be used in the manufacture of the crate.

We claim:

1. A crate composed of a pair of parallel and spaced bottom side bars, upstanding corner posts rising from the ends of said bars, end cross bars connecting the respective pairs of corner posts, the connection between said cross bars and the corner posts being a pivotal one, and said cross bars at one end being also detachable from the corresponding corner posts, and a longitudinal top bar connecting the top ones of the end cross bars and detachable therefrom.

2. A crate having sides and ends which are pivotally connected, the ends of the crate including a top cross bar, a longitudinal bar connecting the top cross bars of the crate ends and detachably connected thereto, said cross bars being composed of aligned sections having slideable connections with the crate sides, and the longitudinal bar having knuckles at its ends in which the abutting ends of the sections removably seat.

3. A crate having sides and ends which are pivotally connected, the ends of the crate including top, medial and bottom cross bars, the bars at one end of the crate being detachable from the sides thereof to render said end of the crate open, said bars also carrying devices for the locking thereof to the sides of the crate; a longitudinal bar connecting the top cross bars of the crate ends and detachably connected thereto, said longitudinal bar having knuckles at its ends through which the said top cross bars pass.

4. A crate composed of a pair of parallel and spaced bottom side bars, upstanding corner posts rising from the ends of said bars, end cross bars connecting the respective pairs of corner posts, the connection between said cross bars and the corner posts being a pivotal one, and said cross bars at one end being also detachable from the corresponding corner posts, a longitudinal top cross bar connecting the top one of the end cross bars and detachable therefrom, and article-supporting means carried by the bottom side bars.

In testimony whereof we affix our signatures.

WILLIAM W. McCLAY.
